A. L. LEATART.
ENGRAVING BLOCK JAW ATTACHMENT.
APPLICATION FILED AUG. 29, 1908.

921,126.

Patented May 11, 1909.

UNITED STATES PATENT OFFICE.

ARLINGTON L. LEATART, OF LOS ANGELES, CALIFORNIA.

ENGRAVING-BLOCK-JAW ATTACHMENT.

No. 921,126.

Specification of Letters Patent.

Patented May 11, 1909.

Application filed August 29, 1908. Serial No. 450,880.

To all whom it may concern:

Be it known that I, ARLINGTON L. LEATART, a citizen of the United States, residing in the city of Los Angeles, county of Los Angeles, and State of California, have invented new and useful Improvements in Engraving-Block-Jaw Attachments, of which the following is a specification.

My invention relates to certain new or improved jaws or clamps which are readily attachable to or detachable from an engraving block, and the object thereof is to provide jaws or clamps that when attached to an engraving block will rigidly hold the article to be engraved while being worked upon. I accomplish this object by means of the improved detachable jaws or clamps described herein and illustrated in the accompanying drawings in which:

Figure 1 is a perspective view of my improved clamping jaws in place on an ordinary engraver's block with a spoon in place in the jaws. Fig. 2 is a longitudinal vertical section of one of the jaws. Fig. 3 is a central vertical section of the parts shown in Fig. 1 showing in cross section the clamping jaws. Fig. 4 is a side elevation of one side of the clamping jaws. Fig. 5 is a top plan of one of the clamping jaws. Fig. 6 is a side elevation of the opposite side of the clamping jaw to that shown in Fig. 4. Fig. 7 is an end elevation of one of the clamping jaws. Fig. 8 is an end elevation of the other end of one of the clamping jaws.

There are two jaws of the same construction, except that one is right and the other left and therefore only one jaw will be described.

The drawings, except Fig. 1, are made upon the scale and from a pair of full sized practical working jaws, and the lines, grooves, arcs, lips or overhanging edges and surfaces, and contours shown in the drawing may be taken as guides in the construction of other jaws for use in an engraver's block.

In the bottom of the jaw is a longitudinal central groove E whose vertical height is a little over half the height of the jaw. In this groove is mounted a U-shaped guide and retaining wire B of spring wire which is secured to the body of the clamp by having its ends passed into sockets C and C' as best shown in Fig. 2. On this guide wire is mounted two attaching pegs A which are adapted to pass into sockets Q' in the head

Q of the engraver's block of any approved construction. These pegs have transverse holes Z into which guide wire B is received so that the pegs can be moved toward or away from each other, and are placed on the 60 guide wire before one end of the same is turned.

In the center and near the bottom of each jaw is a transverse hole N through which passes a guide rod D which keeps the two 65 jaws in alinement as they are moved toward or away from each other so that the respective arcs, curves and depressions of the vertical faces of the jaws may be kept in accurate register or apposition. This guide rod 70 has its ends slightly beveled or tapered and passes beneath guide wire B, slightly springing the same upwardly as it is passed thereunder so as to cause a slight friction to prevent the jaws moving too easily on the rod. 75 Near each end of guide rod D is a small groove K into which guide wire B will spring to prevent the jaws from coming off guide rod D unless extra force is applied thereto. This construction prevents one of the jaws 80 slipping off the guide rod D before the guide wire B of the other jaw has reached the groove in the other end of the guide rod, and also keeps the parts assembled when the jaws are not in place on the engraving block. 85

Referring to Fig. 4, X—X shows the outer circle of a groove whose central line H—H is the arc of a circle, the diameter of which is three quarters of an inch, and Y—Y is the inner line of said groove. It will be observed that this groove widens and deepens toward the upper part of the clamp, and the purpose thereof is to hold signet rings and other like rings when being engraved, as the edges of the ring whether it be large or small 95 will fit sufficiently close to the center line of the groove that when the jaws are brought together by the movement of the head block the ring will be securely held therein. This side of the jaw which for convenience of description herein we will call the first side of the jaw is the right hand side of the jaw shown in Fig. 5 and a plan of said side is shown in Fig. 4. Cutting across the groove whose central line is H—H is a curved groove whose central 100 line is I. This groove is of uniform depth and width and preferably V-shaped in cross section and its upper line is indicated by the letter F, and its lower line by the letter G. Into this groove is received oval bracelets 110

and napkin rings. The center line I is the arc of a circle whose diameter is two and thirteen sixteenths inches. Cutting across the outer ends of the groove whose central line 5 is I is a longitudinal circular groove, whose upper edge is marked by the letter J and whose lower edge is marked by the letter G'. This groove is adapted for holding fountain pens, pencils and penholders. In Fig. 4 this 10 groove has the reference letter W and is the arc of a circle whose diameter is eleven thirty-seconds of an inch. In the top surface on this side of the jaw is a depression about one thirty-second of an inch in depth. The 15 central inner portion of this depression is under cut at the bottom to form a projecting lip which is the arc of a circle between the points marked L—L, Fig. 5, of a circle whose diameter is one and one fourth inches. At 20 each end the contour of the lip between the points marked L—M is also circular, but the diameter of the circle is two inches. The outer surface of the depression terminates on a circular line which is marked J'. The 25 line J' is the arc of a circle whose diameter is one and seven eighths inches. Below the line J' the surface slopes inwardly and downwardly and then outwardly on a curve and terminates just above the curve whose inner 30 line is marked by the letter I thereby forming a curved surface with an overhanging lip designed for holding the bowls of spoons as illustrated in Fig. 1. The depressed upper surface between the points marked L—L 35 with its overhanging lip is designed to hold small watch caps while the surface having the curved overhanging lip between the points L and M is designed for holding larger watch caps.

40 On the other side of the jaw, that is the left hand side of the jaw shown in Fig. 5, and a plan of which side is shown in Fig. 6, in the top surface is a larger groove marked with the letter d which is the arc of a circle whose diameter is one and one half inches. Below, the 45 surface slopes inwardly and downwardly to form a projecting lip for a short distance and then slopes downwardly and forwardly and terminates in an elliptical line as best shown by the line marked O in Fig. 6. This surface 50 is designed to hold watch cases and like structures. As shown in the drawings this curve occupies the larger part of the upper surface of this side of the jaw, but at one end is a depression whose upper surface is a curve marked R which is the arc of a circle three eighths of an inch in diameter. The surface 55 below the curve R slopes downwardly and inwardly for a very short distance and thence slopes outwardly and downwardly, thereby forming a depression for holding collar buttons and like articles. Running longitudinally and cutting across the edges of the curved surfaces whose upper surfaces are marked by d and 60 R is a V-shaped groove whose upper edge 65

is marked by the letter a, its central line by b, and lower line by c, thereby forming a channel in which signet stick pins and bar pins can be held. In that end and below the depression whose upper curved surface is 70 marked R is a vertical depression whose outer edge is circular and is marked T from which, the surface slopes inwardly to the line marked U a distance of about three thirty-seconds of an inch, and then slopes downwardly and outwardly and terminates on the curved line marked S which forms a vertical depression for holding band and oval rings. At the other end is a narrower vertical depression whose outer surface or edge is 75 marked g and is the arc of a circle whose diameter is three quarters of an inch. The surface then slopes inwardly at an angle of about forty-five degrees to a depth of about a sixteenth of an inch and then slopes in a reverse direction the same distance to the back wall of the depression. This end depression holds Tiffany and flat narrow rings.

By this combination of providing two jaws whose vertical and top surfaces are 80 provided with depressions having curved surfaces provided with overhung lips and also straight grooves with curved walls, I am able to provide a tool for attachment to an engraver's block which will retain and firmly 85 hold any species of jewelry that is required to be engraved which will pass within the spread of the jaws, thereby saving handling a large number of tools and attachments which have been heretofore used in connection with 90 engravers' blocks, and also to provide a tool for holding certain configurations of jewelry which heretofore could not be conveniently held by any attachment upon an engraver's 95 block.

Having described my invention what I 100 claim is:

1. An attachment for engravers' blocks, comprising a pair of jaws provided with adjustable attaching pegs in the bottom thereof and having one or more jewelry holding depressions or recesses.
2. An attachment for engravers' blocks, comprising a pair of jaws provided with adjustable attaching pegs in the bottom thereof and having the vertical walls provided with depressions or recesses substantially as described herein, and having transverse central holes near the bottom thereof; and a guide bar extending through said transverse holes.
3. An attachment for engravers' blocks, comprising a pair of jaws each having depressions or recesses substantially as described and a longitudinal groove in the bottom thereof extending to above the center of the body, and having sockets in said body opening into the grooves near the ends thereof and having central transverse holes near the bottom thereof; U-shaped guide wires within said grooves, the ends thereof being

received in said sockets; attaching pegs slidably mounted on said guide wires; and a transverse guide bar in said transverse holes.

4. An attachment for engravers' blocks, comprising a pair of jaws provided with adjustable attaching pegs in the bottom thereof, said jaws having in the vertical faces thereof depressions or recesses adapted to hold articles substantially as described herein, said depressions or recesses being one half in one jaw and the other half in the other

jaw; and means to hold said jaws in alignment so that the different depressions or recesses therein may be held in apposition.

In witness that I claim the foregoing I 15 have hereunto subscribed my name this 24th day of August, 1908.

ARLINGTON L. LEATART.
